PLATE

 Nicholas J. Bruno, 556 Rockland St.,
 Westbury, N.Y. 11590

Filed Oct. 28, 1971, Ser. No. 193,612

Term of patent 14 years

Int. Cl. D7—01

U.S. Cl. D44—15 K

FIG. 1

FIG. 2

FIG. 3

FIG. 4

FIG. 1 is a top plan view of a plate showing my new design;

FIG. 2 is a side elevational view thereof;

FIG. 3 is a cross-sectional view thereof taken on line 3—3 of FIG. 2; and

FIG. 4 is a bottom plan view thereof.

The side opposite that shown is substantially the same as the side that is shown.

I claim:

The ornamental design for a plate, substantially as shown and described.
